US0D1034437S

(12) **United States Design Patent** (10) Patent No.: **US D1,034,437 S**
(45) Date of Patent: ** Jul. 9, 2024

(54) **JUMP STARTER**

(71) Applicant: **Hunan Lianke Technology Co., Ltd**,
Hunan (CN)

(72) Inventors: **Ke Lou**, Hunan (CN); **Zhenbin Zhou**,
Hunan (CN); **Kaijun Zhou**, Hunan (CN); **Changgang Zhang**, Hunan (CN)

(73) Assignee: **Hunan Lianke Technology Co., Ltd**,
Changde (CN)

(**) Term: **15 Years**

(21) Appl. No.: **29/787,010**

(22) Filed: **Jun. 3, 2021**

(30) **Foreign Application Priority Data**

Apr. 7, 2021 (CN) 202130193832.0

(57) **CLAIM**

The ornamental design for a jump starter, as shown and described.

DESCRIPTION

FIG. 1 is a front perspective view of a jump starter showing our new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a front perspective view thereof, shown in a state of use;

FIG. 10 is a rear perspective view thereof, shown in a state of use; and,

FIG. 11 is an enlarged partial view of area 11 shown in FIG. 7.

The dash-dash broken lines in the drawings illustrate portions of the article that form no part of the claimed design. The dot-dash broken lines in the drawings indicate the portions shown enlarged in the drawings and form no part of the claimed design.

1 Claim, 11 Drawing Sheets
